UNITED STATES PATENT OFFICE

ANDREW EKMAN, OF GRAND RAPIDS, MICHIGAN, ASSIGNOR TO WINTERS & CRAMPTON MFG. CO., OF GRANDVILLE, MICHIGAN, A CORPORATION OF MICHIGAN

REFRIGERATOR LATCH

Application filed September 23, 1929. Serial No. 394,461.

This invention relates to latches and is concerned with a particularly novel and exceedingly simple construction of refrigerator latch which can be produced at low cost and in large quantities and sold directly to the refrigerator manufacturers at a minimum price.

It is a primary object and purpose of the present invention to provide a latch capable of use on refrigerator doors and door casings, or in any other similar relation, on other articles having doors which on an outward and upward pull on a depending handle part of the latch structure, the latch is readily and easily disengaged from a keeper therefor mounted on the door jamb, whereupon the door will immediately open by reason of the outward pull on the handle. A further object and purpose of the invention is to provide a latch construction in which a crank arm mounted on a rock shaft in the latch structure is utilized to connect with the keeper, being readily disconnected therefrom on turning the rock shaft. The rock shaft is spring actuated to normally engage the crank arm portion with the keeper, and by use of the crank arm feature of the invention the same may readily ride over an outer cam surface associated with the keeper hook so that when the door is closed an automatic secure engagement with the keeper is obtained without straining the connections by means of which the latch is attached to the door or injuring the connections used to hingedly mount the door.

A still further object and purpose of the invention is to provide a latch structure of the character noted consisting of few parts which are very simply and easily assembled and all permanently secured in their assembled relation when the depending handle of the structure is pivotally connected to the latch housing.

An understanding of the invention may be had from the following description taken in connection with the accompanying drawings, in which,

Fig. 1 is a side elevation showing a fragmentary portion of a door and door casing,

the latch and the keeper therefor being mounted respectively thereon.

Fig. 2 is a front elevation of the construction shown in Fig. 1.

Fig. 3 is an inner elevation of the latch structure which is mounted on the door.

Figs. 4 and 5 are sections through the latch structure substantially in the plane of the length of the handle showing the handle in two extreme positions.

Fig. 6 is a section through the latch structure at right angles to the sections shown in Figs. 4 and 5, the section being taken substantially in the plane of the axis of the handle pivot, and

Fig. 7 is a perspective view illustrative of the handle, the rock shaft and the connecting member between them, the parts being separated.

Like reference characters refer to like parts in the different figures of the drawings.

The latch of my invention is used on a door in association with a keeper which is mounted on the door jamb. The door jamb, indicated at 1, has the keeper permanently secured thereto. The keeper comprises a base 2 from which a post 3 extends outwardly. The post at its outer end is provided with an upwardly extending keeper hook 4, which is formed so as to have an outer cam surface 5 in front of the hook and an inner downwardly inclined wedging surface 6 at the inner side of the hook, as shown.

The latch to engage with the keeper is mounted on the door 7, it being understood that the door is suitably mounted for swinging movement at its opposite vertical edge on the door frame or casing therefor. The latch includes, in its structure, a housing 8 of sheet metal from which integral upwardly and downwardly extending ears 9 project, through which screws pass to fasten the latch securely to the door. The housing near one of its vertical sides has a section 10 cut from the top of the housing and bent inwardly to provide an ear spaced from but parallel to the adjacent side of the housing. The opposite sides of the housing are also formed with alined openings around which are inwardly extending bearing rings 11 pressed inwardly

from the sides of the housing. A rod or shaft 12 is adapted to be mounted for rocking movement in and extend through the bearing rings or sleeves 11. One end of the shaft or rod 12, that nearest the free vertical edge of the door, is extended beyond the side of the housing and has an arm 13 bent at right angles therefrom and then turned outwardly making a keeper engaging part 14, the arms 13 and 14 forming a crank which may engage with the keeper hook or be lifted above the same on rocking the shaft 12.

A coiled spring 15 is disposed around the shaft 12 having one end 16 bearing against an inner side of the housing (see Fig. 3), while the other end is formed into a hook 17 to set in a notch 18 formed in a side of an arm 19 extending from a body 20, the arm 19 freely passing an opening 21 in the rock shaft 12. The arm 19 and the body 20 from which it extends forms a connecting member between the rock shaft and the handle which operates the shaft. Shoulders 22 at the inner end of the arm 19 and the larger body 20 form stops to limit the passage of the arm 19 through the shaft 12 and after the hook 17 of the spring is engaged in the notch 18 this connecting operating member is securely held in place with the shoulders 22 bearing against a side of the shaft 12 shown in Figs. 4 and 5.

The body 20 is of irregular shape and at its inner and under side is formed with a flat shoulder 23, a curved edge 24 is shown, and there is a projection 25 extending from the body in opposition to the arm 19, having opposed sides 26 which in the structure serve as limit stops for the movement of the handle 27.

The operating handle 27 is formed from sheet metal and at its end where it is associated with the housing 8 and passes therethrough, it has a channel form with parallel spaced apart sides 28. A bridging tongue 29 is formed integral with the end of one side 28 and is bent at right angles to extend to and across the end of the other side 28 as best shown in Fig. 7, thereby providing a rectangular opening 30, between the bridging tongue 29 and an end edge of the web which connects the two sides 28 of the handle. It is through this opening 30 that the body 20 of the connecting operating member extends.

The handle is inserted in the opening made by pressing inwardly the section or ear 10 and lies between said ear 10 and the adjacent side of the housing. A pivot pin 31 passes through the sides of the handle, said ear 10 and the adjacent side of the housing as shown in Fig. 6.

The assembly of the structure is simple and easy. The rock shaft 12 is inserted through a side of the housing, the spring 15 placed thereover, wound to a proper tension and then the arm 19 passed through the opening

21 and the hooked end 17 of the spring engaging in the notch 18 of said arm. The handle is inserted in the opening in the top of the housing and a part of the body 20 of the connecting member between the handle and the rock shaft 12 passes through the opening 30 into the handle, after which the pivot pin 31 is put in place and riveted over at its ends. This makes a secure connection of all of the parts, preventing their disengagement from each other or any longitudinal play of the rock shaft 12.

Under the influence of the spring 15 the handle 27 depends or drops so as to occupy the position shown in Figs. 1 and 2. If the door is opened, when it is closed the member 14 rides against the curved cam 5 of the keeper hook until it passes by the nose of the keeper hook, whereupon the spring causes it to move downwardly, engaging against the inclined inner side 6 and thereby drawing or wedging the door snugly to closed position.

To release the latch and open the door the handle 27 is grasped and pulled outwardly. When this occurs the end of the connecting web between the sides 28 of the handle bears against the upper shoulder 26 of the projection 25, turning the parts to the position shown in Fig. 5 or until the bridging tongue 29 comes against the opposite side 26 of the projection 25. When the handle is released after this operation and after the door is opened, the spring turns the latch parts back to the position shown in Fig. 4 and the edge of the tongue 29 comes against the shoulder 23 to hold the rock shaft from further movement.

The construction described is one very economical to produce. The handle, rock shaft, housing and the connecting member between the handle and rock shaft are all easily produced by means of dies. The coiled spring is a very cheap stock article. The assembly is particularly simple and inexpensive. No base plate at the inner side of the latch housing is needed, thereby eliminating an item of cost in the structure. This latch structure has proved very practical for use on refrigerators. The invention is defined in the appended claims and is to be considered comprehensive of all forms of structure coming within their scope.

I claim:

1. In a latch, a housing, a shaft mounted between the sides of said housing for rocking movement and extending beyond said housing at one side thereof, a keeper engaging crank portion located on said projecting end of the shaft, a spring coiled around said shaft bearing at one end against the housing, an operating member connected with the shaft, said coiled spring at its other end having connection with said operating member and said operating member extending radially from said shaft, and a handle pivot-

ally mounted on the housing engaging with the projecting portion of the operating member whereby the shaft may be turned by operating the handle against the force of the spring.

5. 2. In a latch, a sheet metal housing, a shaft mounted for rocking movement between the sides of the housing and extending at one end beyond the adjacent side of the housing, a keeper engaging crank portion located at the projecting end of the shaft, a handle pivotally mounted on the housing and extending at one end through an opening in the housing, an operating member attached to the shaft and projecting therefrom and operatively connected to said handle, and a coiled spring around the shaft having one end connected with the shaft and the other end bearing against the housing.

20. 3. In a latch structure, a sheet metal housing having an opening in its outer side and an ear turned inwardly from said outer side at said opening, a sheet metal handle having an end of channel form inserted through said opening and lying between said ear and a side of the housing, a pivot pin passing through the ear, handle and side of the housing, a rock shaft mounted between the sides of the housing above the handle and having 25 one end extending beyond a side of the housing and provided with a keeper engaging crank portion, an operating member secured to the shaft and extending radially therefrom and entering into the end of the handle between the sides thereof, and spring means acting on said shaft to turn the same in one direction, said means yielding on operating the handle outwardly whereby the shaft may be turned in the opposite direction.

40. 4. A latch structure comprising a sheet metal housing having an opening in its outer side and an ear turned inwardly from said outer side of the housing, at said opening, a handle of said sheet metal formed at one end into channel shape and having spaced apart sides connected by a web, said channel end of the handle passing through said opening in the housing, a pivot pin extending through said ear, sides of the handle and adjacent side of the housing, one side of said handle at the end thereof within the housing having a tongue turned therefrom and bridging the space between the spaced apart sides of said handle, a rock shaft mounted on and between the sides of the housing having one end extending beyond a side of the housing and a keeper engaging crank portion on said projecting end of the shaft, an operating member connected with said shaft and extending radially therefrom and into the opening between the sides of the handle, said tongue and said web, and a coiled spring 45 around said shaft connected at one end there-

to and at the other end bearing against the housing.

5. In a latch structure, a sheet metal housing, a handle depending from said housing and at its upper end extending through an opening in said housing, means pivotally mounting the handle on the housing, a horizontal rock shaft mounted on and between the sides of the housing and having one end portion extending beyond a side of the housing, a keeper engaging crank at the projecting end of the said shaft, means directly connecting the handle and shaft for turning the shaft in one direction on outward movement of the lower end portion of the handle, and spring means coiled about the shaft tending to turn said shaft in the opposite direction.

6. In a latch, a housing, a shaft mounted for rocking movement in the housing, a pivoted handle having an open end, an operating member secured to said shaft and extending therefrom and entering into the end of the handle loosely whereby contact is alternately had between the opposed sides of the operating member and the handle.

7. In a latch, a housing, a shaft mounted for rocking movement in the housing, a handle pivoted in said housing, two spaced apart contact portions on said handle, and an operating member extending radially from said shaft and extending between said contact portions of said handle whereby the operating member is clamped between said contact portions in either of its extreme swinging portions to form limit stops for the movements of the handle and the rock shaft in either direction.

In testimony whereof I affix my signature.

ANDREW EKMAN.
